UNITED STATES PATENT OFFICE.

JAMES M. EVANS, OF WESTPORT, CONNECTICUT, ASSIGNOR TO EVANS ENGINE COMPANY, INCORPORATED, A CORPORATION OF NEW YORK.

CARBURETER.

1,232,258.

Specification of Letters Patent.

Patented July 3, 1917.

Application filed March 31, 1915. Serial No. 18,239.

To all whom it may concern:

Be it known that I, JAMES M. EVANS, a citizen of the United States, and a resident of Westport, in the county of Fairfield and 5 State of Connecticut, have invented certain new and useful Improvements in Carbureters, of which the following is a description.

In my application, Serial No. 866,276, filed 10 October 12, 1914, I have described a carbureter comprising a reservoir chamber for liquid, a mixing chamber and means for conveying charges of liquid from the reservoir chamber to the mixing chamber.

15 My present invention relates to devices of this same character, and has for its object the provision of means for regulating the charges of liquid conveyed to the mixing chamber to thereby vary the relative amount 20 of liquid in the resulting mixture.

Other objects and features of my invention will appear from the following description and the claims appended thereto.

In the drawing, Figure 1 is a longitudinal 25 sectional view of my improved apparatus with the parts adjusted so that the charges of liquid conveyed from one chamber to the other are relatively large;

Fig. 2 is a similar view but showing the 30 parts adjusted from the maximum charge to no charge;

Fig. 3 is a section taken on the line 3—3 of Fig. 1;

Fig. 4 is a section taken on the line 4—4 35 of Fig. 3; and

Fig. 5 is a plan view of a portion of the mechanism illustrated in Fig. 3.

In the drawings, the numeral 1 designates the mixing chamber for the liquid fuel and 40 air and when the device is used with an internal combustion engine this chamber may be a part of the intake pipe or manifold of the engine. The air passes through this chamber and charges of the liquid fuel are 45 delivered to it periodically as may be required. A liquid fuel or reservoir chamber 2 is located adjacent the mixing chamber and is supplied with liquid through the pipe 4. The pressure or head of the liquid should 50 be such as not only to fill the chamber 2, but preferably to keep the liquid therein under slight pressure; but, while preferable, pressure is not required for its successful operation. The numeral 3 designates a passage 55 leading from the fuel reservoir 2 to the mix-

ing chamber 1. 5 designates a reciprocating plunger or carrier for the liquid adapted to slide in the passage 3, connecting the fuel chamber and the mixing chamber. This plunger or carrier is made in two parts, viz., 60 an inner plunger element having a stem 6 and an enlarged head 7, and an outer plunger element 8 mounted as a sleeve on the stem 6 of the inner element and of the same section as the head 7. The inner faces of 65 the element 8 of the head 7 are so shaped as to come in contact when brought together and are preferably perpendicular to the major axes of the outer element 8 and of the head 7. The stem 6 fits snugly into the 70 outer element 8 and is preferably of a circular section, but may be of any section. The head 7 and the outer element 8 are also preferably of circular section and cylindrical in form, but this is not essential. Both 75 the head 7 and the outer element 8 fit snugly in and slide through the passage 3. The length of the passage 3 is greater than the maximum distance between the faces of the head 7 and the outer element 8 when in the 80 cycle of operation. The two plunger elements 6—7 and 8 are independently controlled by cams or other suitable mechanism to cause them to reciprocate between the reservoir chamber and the mixing chamber. 85

The parts above described are substantially the same as those described in my aforesaid application and, in order that the object and effect of my present invention may be more clearly understood, I will now 90 describe briefly the operation of the above described mechanism, assumed for illustration in a vertical position, but it may be operated in any position.

Referring to Fig. 1, the plunger 5 is seen 95 to be substantially in its lowermost position, and the head 7 and plunger 8 are separated the maximum distance, leaving recess 11 therebetween. This recess will be filled with the liquid present in the reservoir 2 100 and upon the upward movement of the plunger 5, the charge of liquid contained in the recess 11 will be drawn up through the passage 3 into the chamber 1, the recess remaining of constant size. When the plunger 5 105 has been moved into the chamber 1, the plunger 8 descends rapidly and closes upon the head 7, thereby forcibly ejecting and spraying in the chamber 1 the charge of liquid, or such of it as remains in the recess. After 110

this discharge of the liquid, the plunger elements are returned to the reservoir chamber 2 and the plunger elements 6—7 then descend relatively to the plunger element 8, 5 until the desired interval or recess exists between the head 7 and the plunger 8. The cycle of operation above outlined is then repeated.

It is apparent from the above that the 10 amount of liquid contained in each charge delivered to the mixing chamber depends upon the size of the recess between the head 7 and the plunger 8, when the parts are in the position shown in Fig. 1. Thus, if the 15 size of this recess is reduced to the proportions shown in Fig. 2, the amount of liquid in the charge will be correspondingly reduced. In order to regulate the charges of liquid delivered to the mixing chamber from 20 the desired maximum as the upper limit to nothing as the lower limit, I have, therefore, provided means for regulating the size of this recess or, in other words, regulating the distance between the head 7 and the plunger 25 8, during the cycle of operation. The means by which I accomplish this regulation will now be described.

The cams 9 and 10 coöperate with the cam rolls 9', 10', to effect the independent reciprocation of the plunger elements 8 and 30 6—7, respectively. In order to vary the extent of relative movement between the two plunger elements, I may adjust in any suitable manner, the actuating means of one of 35 said elements.

In this particular embodiment of my invention, I have shown means for varying the contour of the cam 10 to thereby vary the extent of reciprocation of the plunger 40 element 6—7 and, consequently, the amount of relative movement between the two plunger elements and the size of the recess 11.

The cam 9 is formed in the disk 12, 45 mounted on the shaft 13, which may be driven from any suitable source. The cam 10 is formed in two separate substantially semi-circular disks or cam sections 14, 15, mounted within the disk 12. One of these 50 semi-circular disks here shown as the disk 15 is adjustable relatively to the other of said disks to vary the contour of the cam 10. In Fig. 1, for instance, the disk 15 is in its extreme position away from the disk 55 14; and, in Fig. 2, the two disks are in contact. The adjacent edges of the disks are dove-tailed, as shown at 16, in order to form a complete path for the cam roll 10', irrespective of the position of the disk 15.

60 Any suitable means may be employed for effecting the relative adjustment between these cam sections 14, 15, the means which I have chosen for the purpose of illustration, being shown in Figs. 3, 4 and 5. The disk 65 15 is guided for movement upon the disk 12

by the pins 17, connected to the disk 15 and passing through slots 17' in the disk 12. Secured to these pins 17, on the opposite side of the disk 12, is the plate 18, to which is secured the actuating pin 19, which co- 70 operates with a cam slot 20, in the disk 21. Thus, it is seen that by turning the disk 21 relatively to the disk 12, the pin 19, and consequently the disk 15, will be moved toward or from the disk 14, to vary the contour 75 of the cam 10, as above described. The means illustrated for moving the disk 21 relatively to the disk 12 consists of the longitudinally shiftable sleeve 22 mounted on the extended hollow hub 23 of the disk 80 21, a pin 24 passing through the sleeve 22, hollow hub 23 and shaft 13, and means such as the lever 25 for shifting the sleeve 22 longitudinally of the shaft 13. The pin 24 passes through circular holes 26 in opposite 85 sides of the sleeve 22 and is secured therein. It also passes through the diagonal slots 27, in opposite sides of the hollow hub 23, and through the longitudinal slot 28 in the shaft 13.

90 During the normal operation of the device, power is transmitted from the shaft 13, through the pin 24, to rotate the disk 21 and sleeve 22 synchronously with the rotation of the disk 12, to which the shaft is secured by 95 some suitable means, such as the pin 29. When, however, it is desired to vary the amount of liquid delivered to the mixing chamber in each charge or, in other words, to regulate the charges, the sleeve 22 is adjusted longitudinally of the shaft 13, by 100 means of the lever 25, with the result that the pin 24 is moved longitudinally in the longitudinal slot 28 of shaft 13, thereby having a camming effect on hub 23 through the diagonal slot 27, and turning this hub and the disk 21 with relation to the shaft 13. This results in a relative rotary movement 105 between the disk 21 and disk 12 and, through the action of the pin 19 and cam slot 20, 110 effects the desired movement of the disk 15 with respect to the disk 14.

From the above it is apparent that I have provided convenient and accurate means for regulating the charges of liquid delivered 115 from the reservoir chamber to the mixing chamber, which means may be operated equally well whether the machine is stationary or in operation.

I have shown a particular embodiment 120 of my invention as an illustration of an operative mechanism in connection with which it may be used, but I do not wish to limit my invention to this or any particular embodiment thereof, since many changes 125 may be made therein by those skilled in the art without departing from the spirit of my invention.

What I claim is:

1. In a device of the kind described, the 130

combination of a reservoir chamber for liquid; a mixing chamber for the passage of air or other gas; a passage connecting the two chambers, a carrier for the liquid adapted to move through said passage from one chamber to the other, said carrier comprising two relatively movable parts; a cam for independently moving each of said parts; and means for adjusting one of said cams to vary the amount of relative movement between said parts, substantially as described. 35

2. The combination of a reservoir chamber for liquid; a mixing chamber for the passage of air or other gas; a passage connecting the two chambers; a carrier for the liquid adapted to move through said passage from one chamber to the other, said carrier comprising two relatively movable parts; a cam for independently moving each of said parts; one of said cams comprising two cam sections; and means for adjusting one of said cam sections relatively to the other to vary the amount of relative movement between said parts, substantially as described. 40

3. In a device of the kind described, a combination of a reservoir chamber for liquid; a mixing chamber for the passage of air or other gas; a passage connecting the two chambers; a carrier for the liquid adapted to move through said passage from one chamber to the other, said carrier comprising two relatively movable parts; a cam for independently moving each of said parts, 45 one of said cams comprising two cam sections; and means for adjusting one of said cam sections relatively to the other to vary the amount of relative movement between said parts, comprising a cam disk operatively connected to the first mentioned cam section; a longitudinally shiftable sleeve mounted on said cam disk, and means for shifting said sleeve to thereby move the cam disk relatively to said first mentioned cam 50 section, substantially as described. 55

JAMES M. EVANS.
